UNITED STATES PATENT OFFICE.

FRED N. LA CHAPELLE, OF BEVERLY, MASSACHUSETTS, ASSIGNOR TO UNITED SHOE MACHINERY COMPANY, OF PATERSON, NEW JERSEY, A CORPORATION OF NEW JERSEY.

MACHINE FOR OPERATING ON SHOE-SOLES.

1,217,122.

Specification of Letters Patent. Patented Feb. 20, 1917.

Application filed April 19, 1913. Serial No. 762,175.

To all whom it may concern:

Be it known that I, FRED N. LA CHAPELLE, a citizen of the United States, residing at Beverly, in the county of Essex and State 5 of Massachusetts, have invented certain new and useful Improvements in Machines for Operating on Shoe-Soles; and I do hereby declare the following to be a full, clear, and exact description of the invention, such as 10 will enable others skilled in the art to which it appertains to make and use the same.

This invention relates to machines for operating upon the soles of shoes, and particularly to machines for preparing insoles 15 of lasted shoes for sewing.

When the lasting operation has been completed, the leather of the insole, even though it has been tempered in some prior operation, is usually hard and brittle and consequently unfit for sewing. It is therefore essential before the shoe is presented to the 20 insole or other sewing machine, for the purpose of attaching the upper and insole together by stitches passing through the upper and the between substance of the insole, to temper thoroughly the between substance so that the needle will penetrate the material easily and make a clean puncture therethrough, and so that the thread will not cut 25 into the leather to any considerable extent when the stitches are drawn taut. The insole is often tempered by dipping the sole of the lasted shoe in water. This is objectionable, since it often results in staining the 30 lining of the shoe and the leather of the upper. It is frequently the practice to moisten the between substance by running a wet brush along the same, or by discharging water from a can having a tapered nozzle 35 which the operator runs along the channel. These hand operations are slow and laborious, and it is difficult to moisten the between substance thoroughly and uniformly by either of these last mentioned 40 methods. During the lasting operation the channel lip of the insole is often bent down close to the body of the insole, making it difficult to insert the channel guide of the sewing machine in the channel. The resistance 45 of the lip when it lies down close to the body of the insole may cause the channel guide during the sewing operation to leave the base of the channel or even to become completely disengaged from the chan-

nel. It is therefore the practice to turn the 55 lip away from the body of the insole and thereby open the channel just before the shoe is sewed. This operation is usually performed by means of a hand tool.

One object of the invention is to produce 60 a machine by which, before the lasted shoe is presented to a sewing machine for attaching the upper and insole together, the operator may thoroughly moisten the between substance of the insole quickly and 65 easily without wetting other portions of the shoe.

Another object of the invention is to produce 70 a machine by which in one operation the between substance of the insole of a 75 lasted shoe may be moistened and the channel lip turned out away from the body of the insole to prepare the shoe for subsequent sewing operations.

With these objects in view the invention 75 contemplates the provision of various novel and advantageous features set forth in the following description and pointed out in the claims.

The features of the invention will be 80 readily understood from an inspection of the accompanying drawings illustrating the preferred form of the invention, and the following detailed description thereof.

In the drawings, Figure 1 is a side elevation of a machine embodying the invention; Fig. 2 is a fragmentary view in vertical section illustrating a portion of the mechanism for controlling the discharge of liquid through the nozzles of the wetting 85 device; Fig. 3 is a detail view partly in horizontal section illustrating a portion of the mechanism for controlling the discharge 90 of liquid through the nozzles of the wetting device; and Fig. 4 is a fragmentary perspective view illustrating the lip lifting tool, the nozzles of the wetting device, and 95 a shoe in operating position with relation to the tool.

The machine illustrated in the drawings 100 comprises a rotary lip lifting tool which is arranged to engage in the channel of the insole and to lift and turn back the channel lip. This tool, indicated at 1, is mounted 105 to rotate on a substantially vertical axis, and is provided with a series of flat faces which successively engage the lip with a sharp impact to set the lip in upturned posi-

tion. The manner in which the tool engages the lip is illustrated particularly in Fig. 4. The tool is secured in any suitable manner, as by means of a threaded shank, to the lower end of a substantially vertical rotary shaft 3 mounted to rotate in spaced bearings 4 and 5 in the forward end of an arm 6 on the frame of the machine. A pulley 7 is fixed to the shaft 3, and the shaft is rotated by means of a belt 8 passing about said pulley and extending rearwardly therefrom about two pulleys, one of which is shown at 9. The belt extends from the pulleys 9 about any suitable driving pulley (not shown). The tool is preferably rotated in such a direction that the lip engaging face of the tool moves in the opposite direction from that in which the shoe is fed, so that the tool will have a marked wiping action on the lip. In the illustrated embodiment of the invention the tool is rotated in a left-hand direction, and in the operation of the machine the shoe is fed from left to right, as indicated by the arrow in Fig. 4.

The machine is provided with a moistening device comprising a tank 10 for the reception of any suitable moistening liquid, with which tank is connected a discharge pipe 11. This pipe extends downwardly and forwardly to a point adjacent the shaft 3, and is provided with a pair of discharge nozzles 12 and 13 arranged on opposite sides of the lip lifting tool. The end of the nozzle 12 is flattened to form a narrow mouth arranged to extend transversely to the channel when operating upon the insole. The end of the nozzle is located in advance of the tool with relation to the direction of feed, and is placed with relation to the lip lifting tool so that it discharges upon the outer face of the channel lip and the between substance adjacent thereto. The lip and the substance at the base of the lip are moistened by the liquid discharged from the nozzle 12 before the lip is acted upon by the tool, thereby enabling the tool to lift the lip more easily than if the lip were dry when it reached the tool. Since the lip is moistened when it is acted upon by the tool, the lip tends to retain its upward position after it is lifted. The nozzle 13 is arranged to the rear of the tool in the direction in which the shoe is fed, and is flattened at its extremity to form a narrow mouth extending parallel with the channel of the insole. The extremity of the nozzle 13 is placed with relation to the lip lifting tool, so that when the machine is in operation it extends down fairly close to the bottom of the channel, and the liquid discharged from this nozzle thoroughly moistens the base of the lip and the between substance at the bottom of the channel. The liquid discharged from the nozzle 12 upon the outside of the between substance, and the liquid discharged from

the nozzle 13 within the channel, soaks into the leather and thoroughly impregnates the between substance with moisture.

It is essential for the satisfactory working of the machine that the discharge of liquid from the tank 10 through the pipe 11 be controlled so that the liquid flows through the discharge nozzles when the machine is operating upon a shoe, and that when the shoe is removed from the machine the flow of liquid through the nozzles is arrested. In presenting the various portions of the shoe to the action of the lip lifting tool and the moistening device, the operator requires the use of both hands to hold and manipulate the shoe. In the present invention, means is provided by which the operator, after placing the shoe in operating position with relation to the tool, by a simple and convenient movement of the shoe may open the discharge outlet of the tank 10 connected with the pipe 11, and which acts when the shoe is removed to close the discharge outlet and cut off the supply from the discharge nozzles. In the construction illustrated, the supply tank 10 is provided with a discharge opening 14, and the flow of liquid through said opening is controlled by a valve. This valve is constructed as illustrated in Fig. 2, and comprises a head 15 which engages a suitably shaped seat formed by the wall of the discharge opening. The valve is provided with a valve stem 16 connected with the head which slides through a suitable opening in a valve casing 17 secured to the base of the supply tank, and the valve is held normally in engagement with the valve seat by a coiled spring 18 surrounding the valve stem and engaging the head 15 and the valve casing at its respective extremities. The liquid from the tank flows into the valve casing through openings 19 formed in said casing. The discharge opening 14 leads from the supply tank to a chamber formed by a housing 20, in which chamber is located a portion of the valve operating mechanism. Said mechanism comprises an arm 21 mounted on a rock shaft 22 journaled in the housing 20, the forward end of which arm engages beneath a downwardly projecting nose on the head of the valve. The shaft 22 is journaled at one extremity in a step bearing 23 formed in the housing. The other bearing 24 for said shaft is formed by a bore through the housing, and the shaft 22 extends through the bearing 24 and projects beyond said bearing outside the housing. A second arm 25 is secured to the shaft 22 outside the housing 20, and extends forwardly over the upper end of the vertical shaft 3 which carries the lip lifting tool. In the mechanism described, by lifting the outer end of the arm 25, the arm 21 will be raised therewith, and will

lift the valve from its seat and permit the liquid to flow through the discharge opening 14 into the chamber formed by the housing 20. The discharge pipe 11 is connected 5 with the interior of said housing. The shaft 3 is arranged for vertical movement in its bearings 4 and 5, so that when the shoe is engaged with the lower end of the tool by pressing the shoe upward or in the direction of the axis of the shaft, the shaft may 10 be lifted vertically. The upward movement of the shaft is limited by the engagement of a stop collar 26 with the upper bearing 5 of the shaft, and the downward movement 15 of the shaft in its bearings is limited by the engagement of the pulley 7 with the lower bearing 4. The arm 25 is normally held by gravity in engagement with the upper end of the shaft 3. The parts are 20 constructed and arranged so that when the shaft 3 is in its lowermost position, with the pulley 7 in engagement with the bearing 4, the valve is closed and the flow of liquid through the pipe 11 is arrested.

25 In presenting the shoe to the machine, the operator holds the shoe with the portion of the margin of the sole at which he desires to begin the operation substantially parallel with the line between the ends of the nozzles 30 of the wetting device, and then manipulates the shoe to engage the tool beneath the channel lip. When the shoe is thus engaged with the tool, by a slight upward pressure of the work against the lower end of the 35 tool, the shaft 3 is raised in its bearings, thereby raising the forward end of the arm 25 which is in engagement with the upper end of the shaft, and raising the arm 21 to open the valve. The operator maintains 40 this upward pressure of the work against the lower end of the tool while manipulating the shoe to bring the different portions of the margin thereof into operating position with relation to the tool and to the 45 nozzles of the wetting device. The upward pressure of the shoe against the lower end of the tool holds the tool firmly in the channel and keeps the valve of the wetting device open so that the moistening liquid may 50 flow freely from the nozzles during the operation of the machine. When the lip lifting and wetting operation has been completed, and the shoe is moved downwardly to disengage it from the tool, the shaft 3 55 descends, thereby permitting the arms 25 and 21 to descend, and the valve to be closed by the action of the coiled spring 18. The liquid which is in the pipe 11 and in the discharge nozzles 12 and 13, when the valve 60 is closed, will be held from flowing out of the mouths of the nozzles by the pressure of the air.

While the invention has been illustrated as embodied in a machine which is designed 65 particularly for wetting the between sub-

stance of the insole of a lasted shoe, and for lifting the lip of the insole, certain features of the invention are not limited to machines for operating upon insoles, but may be employed in treating other parts of a shoe 70 either before or after the parts are assembled on a last. It is also to be understood that except as defined in the claims the invention is not limited to any particular construction or arrangement of parts.

Having explained the nature and object of the invention, and having specifically described a machine embodying the invention in its preferred form, what is claimed is:—

1. A machine for operating upon the insoles of shoes, having, in combination, a lip lifting tool, means for discharging liquid upon the outer face of the insole along the channel lip in advance of the tool, and means for discharging liquid within the 85 channel after the lip is lifted by the tool.

2. A machine for operating upon shoe soles, having, in combination, a movable lip lifting tool, means for operating the tool to lift the lip, and means to moisten the lip 90 before it is acted upon by the tool.

3. A machine for operating upon shoe soles, having, in combination, a lip lifting tool arranged to enter the channel of the sole and lift the lip from the sole, a moistening device comprising a source of liquid supply, a pipe leading therefrom, a valve for controlling the supply of liquid through the pipe, means arranged for operation by movement of the work when the tool is in 100 engagement with the work for opening the valve, and means for closing the valve when the work is moved to disengage it from the tool.

4. A machine for operating on shoe soles, 105 having, in combination, a lip lifting tool arranged to enter the channel of the sole and lift the lip from the sole, a moistening device comprising a source of liquid supply, a pipe leading therefrom, a valve for controlling the flow of liquid through the pipe, means operated by the pressure of the work against the tool for opening the valve, and means for closing the valve as the work is moved to disengage it from the tool.

5. A machine for operating on shoe soles, having, in combination, a rotary lip lifting tool, a shaft upon which the tool is mounted arranged for axial movement, a moistening device comprising a source of liquid 120 supply, a valve for controlling the discharge of liquid therefrom upon the work, and means operated by the axial movement of the shaft for opening and closing the valve.

6. A machine for operating on shoe soles, 125 having, in combination, a rotary lip lifting tool for turning back the lip of the sole, means to rotate the tool, and a moistening device acting in advance of the tool.

7. A machine for operating on shoe soles, 130

having, in combination, a lip lifting tool, means for moistening the lip and the substance of the sole adjacent thereto before the lip is acted upon by the tool, and means 5 for moistening the substance within the channel after the lip is lifted by the tool.

8. A machine for operating on shoe soles, having, in combination, a source of liquid supply, a nozzle connected with said supply 10 and having an elongated discharge opening extending transversely to the channel for discharging liquid upon the outer face of the sole along the channel, and a second nozzle connected with said supply and having 15 an elongated discharge opening arranged parallel with and extending down into the channel for discharging liquid inside the channel.

9. A machine for operating on shoe soles, 20 having, in combination, a lip lifting tool, and means for discharging liquid within the channel after the lip is lifted by the tool.

10. A machine for operating on shoe soles, having, in combination, means for lifting 25 the lip, a source of liquid supply, and a pair of nozzles for discharging liquid at different points on the sole in proximity to the lip lifting means to temper the sole.

11. A machine for operating on shoe soles, 30 having, in combination, a source of liquid supply, a nozzle connected with said supply and having an elongated discharge opening extending transversely to the channel for discharging liquid upon the outer face of the sole along the channel, a second nozzle 35 connected with said supply and having an elongated discharge opening arranged parallel with and to extend down into the channel for discharging liquid inside the channel, a valve for controlling the discharge of 40 liquid from the nozzles, and means controlled by the presentation of the work to and the removal of the work from the machine for opening and closing the valve.

45 12. A machine for operating upon the parts of shoes, having, in combination, an operating tool and means for discharging liquid upon the work in proximity to the tool both before and after it is acted upon 50 by the tool.

13. A machine for operating upon the parts of shoes, having, in combination, an operating tool, a source of liquid supply, and a pair of nozzles connected with said 55 supply and arranged to discharge the liquid

in proximity to the tool at different points on the work relative to said tool.

14. A machine for operating upon the parts of shoes, having, in combination, an operating tool, a source of liquid supply, and a pair of nozzles connected with said supply and arranged upon opposite sides of said tool.

15. A machine for operating upon shoe soles, having, in combination, a lip lifting 65 tool and means for discharging a moistening liquid upon the work before it is acted upon by the tool.

16. A machine for operating upon shoe soles, having, in combination, a lip lifting 70 tool, and means for discharging a moistening liquid upon the work after it is acted upon by the tool.

17. A machine for operating on shoe soles, having, in combination, a lip lifting tool, 75 means for actuating the tool independently of its progressive movement relative to the work to turn the lip and set the same in upturned position, a moistening device for discharging a moistening liquid upon the work 80 during the operation of the tool comprising a source of liquid supply, a pipe leading therefrom, a nozzle connected with the pipe through which the moistening liquid is discharged upon the work, a valve for controlling 85 the flow of liquid through the nozzle, means operated by the movement of the tool produced by the pressure of the work against the tool to open the valve, and means to close the valve when the pressure of the work 90 against the tool is relieved.

18. A machine for operating on shoe soles, having, in combination, a lip lifting tool, means for actuating the tool independently of its progressive movement relative to the 95 work to turn the lip and set the same in upturned position, a moistening device for discharging a moistening liquid upon the work during the operation of the tool comprising a source of liquid supply, a pipe leading 100 therefrom, a nozzle connected with the pipe through which the moistening liquid is discharged upon the work, a valve controlling the flow of liquid through the nozzle, and means under control of the operator for 105 opening and closing the valve.
